US0D1096149S

(12) **United States Design Patent** (10) **Patent No.:** **US D1,096,149 S**
(45) **Date of Patent:** **** Oct. 7, 2025**

(54) **BAND**

(71) Applicant: **The Ridge Wallet LLC**, Santa Monica, CA (US)

(72) Inventor: **Daniel Kane**, Agoura Hills, CA (US)

(73) Assignee: **The Ridge Wallet LLC**, Santa Monica, CA (US)

(**) Term: **15 Years**

(21) Appl. No.: **29/925,946**

(22) Filed: **Jan. 26, 2024**

Related U.S. Application Data

(63) Continuation of application No. 18/107,955, filed on Feb. 9, 2023, now Pat. No. 12,089,704, which is a continuation of application No. 18/076,188, filed on Dec. 6, 2022, now abandoned, which is a continuation of application No. 17/490,201, filed on Sep. 30, 2021, now abandoned, which is a continuation of application No. 17/035,261, filed on Sep. 28, 2020, now Pat. No. 11,596,212, which is a continuation of application No. 15/421,596, filed on Feb. 1, 2017, now Pat. No. 10,791,808, which is a (Continued)
